UNITED STATES PATENT OFFICE.

RICHARD C. LEAKE, OF ROCHESTER, NEW YORK, ASSIGNEE TO GENERAL RAILWAY SIGNAL COMPANY, OF ROCHESTER, NEW YORK, A CORPORATION OF NEW YORK.

MECHANICAL TIME RELEASE.

Application filed February 10, 1920. Serial No. 357,639.

To all whom it may concern:

Be it known that I, RICHARD C. LEAKE, a citizen of the United States, and resident of the city of Rochester, in the county of Monroe and State of New York, have invented a new and useful Mechanical Time Release, of which the following is a specification.

This invention relates to mechanical time releases which are particularly adapted for use in connection with the levers of interlocking machines for railways.

Mechanical time releases are commonly applied in practice to a lever of an interlocking machine for the purpose of preventing movement of said lever from one position to another until after the lapse of a predetermined time. When the release is applied to a lever, for example, a signal lever, the operator in a tower, having set up a route for an approaching train and cleared the signal, may return the lever to its normal indication position and put the signal to stop; but on account of the time release mechanism, the operator is prevented from returning the lever to its full normal position so as to release the mechanical locking of a conflicting route, until after the lapse of a predetermined time for which the time release is adjusted. One form of a mechanical time release of this type is disclosed in the patent to H. B. Taylor, No. 1,245,133, dated October 30, 1917; and the present invention is an improvement upon this particular construction.

One object of the present invention is to improve the construction of mechanical releases of the type described and provide a simple, reliable and efficient device, which comprises few and simple parts, and which can be easily and cheaply manufactured.

Other detail objects and advantages will appear hereinafter during the description of the invention.

In describing the invention in detail, reference will be made to the accompanying drawings, in which like reference characters designate corresponding parts in the several views, and in which—

Figure 1 is a side elevation of my improved time release mechanism applied to a lever of an interlocking machine, one of the side plates of the mechanism being

broken away and some parts shown in section for the sake of clearness;

Fig. 2 is an enlarged horizontal section taken substantially on the line 2—2 in Fig. 1, with the cover and base omitted;

Figs. 3 and 3^A are detail views;

Fig. 4 is a diagrammatic view, partly in perspective, with certain parts broken away and spread apart for the sake of clearness, which shows in a simplified manner the principal operating parts of my improved time release mechanism in positions corresponding to the normal position of the lever;

Fig. 5 is a fragmentary view similar to Fig. 4, which shows the positions of the lock bolt, the driving plunger and associated parts when the lever is in the reverse position;

Fig. 6 is a vertical transverse section on the line 6—6 in Fig. 1, and

Fig. 7 is a fragmentary horizontal section on the line 7—7 in Fig. 1.

The mechanical time release mechanism embodying my invention comprises in general a base A which is secured to the lever guides by bolts or other suitable means (not shown) above the usual slidable bar or lever L. This base A is provided near its ends with integral lugs 1 to which rectangular side plates 2 are fastened by screws 3. These side plates 2 constitute the supports for the various operating parts and are connected together by spacing studs 4 in the way commonly employed in clock-work mechanisms. The timing mechanism is of the clockwork type, and comprises a train of gears, mounted on transverse shafts supported by the side plates 2, and driven by a coiled spring 5. The spring 5 is secured at one end to a main shaft 6 by the usual pin and slot connection, and its other end is looped around a pin 7 fixed in one of the side plates 2, said spring being confined by smaller pins 8 fixed in said side plate.

The main shaft 6 is connected by a pawl and ratchet of ordinary construction to the first gear wheel 9 of the gear train. In the construction shown (see Fig. 3) the gear 9 carries spring pressed pawls 10 which cooperate with the teeth of a ratchet wheel 11 fastened to or integral with said main shaft 6, in such a manner that when the main shaft is rotated in one direction, coil

spring 5 is wound up without operating the gear train, and when the spring is permitted to unwind, the main shaft drives the gear train. The gear train includes a pinion 12 on a shaft 13, a large gear 14 driven by said pinion, and a second pinion 15 on a shaft 16. An escapement wheel 17 is secured to the shaft 16, and a weighted pallet 18 loosely mounted on a transverse shaft or pin 19, 5 cooperates with said escapement wheel 17 to limit the speed at which the gears in the train may rotate while driven by the spring 5. The arms of the pallet 18 are provided with holes by means of which additional 10 weights 20 (see Fig. 3^A) may be added to change the weighting of said pallet and thus vary the timing of the apparatus. The clockwork mechanism above described is wound up and automatically released by 15 the lever L. To the main shaft 6 is fixed a pinion 21 which meshes with a gear sector 22 loosely journaled on a shaft 23 supported in the side plates 2. This gear sector 22 has an arm 24 in which is threaded a vertically 20 adjustable screw 25, the end of said arm being split and provided with a clamping screw 26 (see Fig. 2) for the purpose of locking the adjusting screw 25. Loosely 25 journaled on the shaft 23 are two parallel 30 rocking levers 27, preferably arranged on opposite sides of the sector gear 22 and spaced from the adjacent side plates 2 by collars 28. These levers 27 are connected near one end by two transverse pins 29 and 35 30 held in place by cotter pins. One pin 30 is connected to the upper end of a vertically movable driving plunger 31 which extends downward between two rocking levers 27 (see Figs. 4 and 7) and passes 40 loosely through a guiding hole in the base A, the lower end of said plunger being beveled for the purpose hereinafter explained. The other pin 29 is arranged to strike the adjusting screw 25 when the driving 45 plunger 31 and the levers 27 are raised.

Between the inner ends of the levers 27 is a vertically movable lock bolt B which has a lower rounded portion 32 extending downward through a guiding hole in the 50 base A. The upper portion of this bolt B is bifurcated or split to form two side portions 33 straddling the gear sector 22 (see Fig. 6); and said bolt is guided near its upper end by two transverse pins 34 secured to the side plates 2. Near the upper end of the bolt B is a transverse pin 35, and on each side of said bolt is a plunger 36 having an enlarged eye loosely mounted 55 on said pin 35 and held thereon by a cotter pin. The lower end of each plunger 36 is guided in an angle bracket 37 secured to the corresponding side plate 2. A compression spring 38 surrounds each plunger 36, and bears against the bracket 37 and the 60 head of said plunger, so as to urge said

plunger and lock bolt B upward to the position shown in Figs. 1 and 4, said upward movement being limited by a small transverse pin in each plunger 36 engaging the corresponding bracket 37. Each side portion 33 of the lock bolt B is cut away to leave a shoulder 40 arranged to be engaged by a latch dog 41 pivotally mounted on a pin 42 fixed in the side plates 2. This latch dog 41 is thrown into its latching position 70 by a spring 43, and is disposed so as to be struck and released by a shoulder 44 of the gear sector 22 (see Figs. 4 and 5). Fixed in the bolt B below levers 27 is a pin 39.

In the construction illustrated I have 80 made provision for the operation of a circuit controller in conjunction with the locking and unlocking of the bolt B. This circuit controller comprises a contact pin 45 extending transversely through a block 46 of insulating material which is secured to the upper end of the lock bolt B by the pin 35 which supports the plungers 36. This contact pin 45 is arranged to bridge a pair of fixed contact fingers 47, when the lock bolt B is raised. These contact fingers 47, together with their retainers 48 are clamped by binding posts 49 to a block 50 of insulating material which rests on the top edges of the side plates 2 and which is clamped thereto by a hook bolt 51 (see Fig. 1). To protect the mechanism from dirt or malicious tampering, it is preferably enclosed in a suitable sheet metal cover 52, which is held in place by a thumb nut 53 on the hook bolt 51, a suitable seal being provided for this thumb nut 53, if desired.

For the purpose of informing the operator that the lock bolt B has been withdrawn, I provide a striker 54 which comprises a ball on the end of the wire loosely mounted on one of the guide pins 34, said rod being struck by the jump of the lock bolt B to its unlocked position and being thereby flung against the cover 52 so as to give a distant click.

For the purpose of illustrating and explaining the operation of my improved time release mechanism, I have shown it in connection with one of the slideable levers used in one well known type of interlocking machine. This lever L comprises a rectangular bar mounted edgewise in suitable guides (not shown) so that it may be slid back and forth, a suitable handle being provided to facilitate its manual operation. This lever L has a cam slot 56 (see Figs. 1 and 4) formed thereon in which is disposed a roller 57 carried by the upper end of a tappet rod 58 forming part of the usual mechanical interlocking of such machines. In the upper edge of the lever L a notch is cut out to form a shoulder 59 and an incline 60. The lever has four significant positions, a full normal position shown in Figs. 1 and 4, a 100

normal indication position, a reverse indication position shown in Fig. 5 and a full reverse position. In connection with the operation of this invention, it should be understood that when the lever is moved from the full reverse position, the mechanical interlocking is not released until the lever reaches its full normal position and moves the roller 57 and tappet bar 58 to its lowermost position; and the purpose of my time release mechanism is to prevent such movement to the full normal position until after the lapse of a certain time.

Operation.—The lever L is shown in Figs. 1 and 4 in its full normal position, and the parts of the time release mechanism in corresponding position. When the lever L is moved to the reverse indication position shown in Fig. 5 (to the right as viewed in Figs. 1 and 4) the incline 60 of the notch in said lever engages the beveled end of the driving plunger 31 and forces it upward, thereby rocking the levers 27 which in turn strike pin 39 and project the lock bolt B downward, against the opposition of the springs 38, to the position in back of the shoulder 59, as shown in Fig. 5. During this upward movement of the driving plunger 31, the adjusting screw 25 is struck by the pin 29 in the levers 27, after the space normally intervening between said pin and screw has been taken up, and thus rocks the gear sector 22, rotating the pinion 21 and the main shaft 6 in the counterclockwise direction, thereby winding up the coil spring 5 without turning the gear 9, since the pawls 10 click idly over the teeth of the ratchet wheel 11. As the gear sector 22 is moved, the latch dog 41 is swung by the spring 43 into engagement with the shoulders 40 on the lock bolt B. As long as the lever L remains in the reverse or reverse indication position, the driving plunger 31 is held up and the parts of the timing mechanism cannot operate.

If now the lever L is moved toward its normal position (to the left as viewed in Fig. 5), the shoulder 59 strikes the lock bolt B and prevents movement of said lever beyond the normal indication position. The driving plunger 31, however, is no longer held up, and the coil spring 5 is free to rotate the main shaft 6 clockwise, driving gear 9 through pawls 10 and ratchet wheel 11, and the escapement wheel 17 through the other gears of the train. As the escapement wheel 17 is rotated, the pallet 18 is oscillated, so that this return movement of the main shaft 6 takes place slowly at a rate determined by the weight of the arms of the pallet 18. After the lapse of time for which the device is adjusted, the gear sector 22 is moved by the coil spring 5 far enough to trip the latch dog 41, thereby releasing the lock bolt B and permitting it to be snapped up

by the springs 38. This releases the lever L and permits it being moved to its full normal position. The operator is advised of the unlocking operation by the click of the striker 54 on the cover 52.

From the foregoing it can be seen that my time release mechanism prevents a lever being returned to its full normal position, after it has been moved to the reverse position, until after the lapse of a predetermined interval of time. Thus, after the operator has set up one route, and has cleared the signal governing traffic over this route by putting the lever L to the reverse position, he is able to change the signal back to stop, preparatory to changing the route, by putting the lever L back to its normal indication position, but is unable to put the lever back to its full normal position and release the mechanical interlocking controlling the levers for the switches, derails or the like of the route in question.

If, therefore, the signal governing the route has been cleared and a train has accepted that signal, there will ordinarily be time enough for the train to pass through the plant before the operator can change the switches or derails of the route. Other features and advantages of such a time check upon the operator as is provided by my invention are well known in practice and need not be specifically explained.

The time of operation of the device may be adjusted by screwing the adjusting screw 25 in or out, thus varying space between said screw and the pin 29. This in turn varies the extent to which the gear sector 22 is rocked, and, therefore, the amount of timed movement it must make when released before tripping the latch dog 41. The timing may also be varied by changing the weight of the arms of the pallet 18.

The construction of the time release mechanism shown and described comprises in general the same organization and arrangement of parts disclosed in the Taylor patent above mentioned; and for brevity this prior construction will be referred to in the claims as the time release mechanism of the character described.

Regarding the specific improvements constituting the present invention, among other things it will be noted that the lock bolt B is suspended from its upper end, being guided at its lower end by the hole in the base A and at its middle by the pins 34 bearing against its edges. This construction prevents binding or wear of the parts, since the springs 36 act directly on line with the bolt to lift it without forcing it sidewise.

In addition to the adjustment of the time interval of the mechanism afforded by the screw 25, which varies the extent of winding movement of the time controlled mechanism, provision is made for easily changing

the weight of the pallet 18, so as to adapt the parts for a wider range of timing operation than could be conveniently obtained by adjustment of the screw 25.

5 The circuit controlling feature may be used or omitted, as desired. Its use provides for the opening and closing of a circuit corresponding to the locked and unlocked position of the lever, this circuit for instance being the indication circuit; and in some arrangements such circuit controlling means may be used to advantage.

Obviously, the exact construction shown and described may be modified and changed 15 without departing from my invention, and I desire to have it understood that the particular embodiment selected is merely illustrative.

What I claim as new and desire to secure 20 by Letters Patent of the United States, is:

1. In a time release mechanism of the character described, the combination with a lever, a vertically movable locking bolt actuated by said lever and adapted to prevent 25 movement of said lever in one direction in a predetermined position thereof, and circuit controlling means automatically opened and closed in correspondence with the movement of said bolt to its locking and unlocking 30 positions.

2. In a time release mechanism of the specific character described, the combination with a lever, a vertically movable locking bolt automatically projected by the movement 35 of said lever into position to lock said lever against movement in one direction in a predetermined position thereof, a circuit controller actuated by said bolt and opened and closed respectively as the bolt assumes 40 its locking and unlocking positions.

3. A mechanical time release for levers of interlocking machines, comprising two side

plates arranged side by side and separated by spacing studs, a contact block mounted on the edges of said side plates and clamped in position by a hook bolt adapted to hook under one of said spacing studs and provided with clamping nuts for holding the block, circuit controlling means carried by said contact block and secured thereto by binding posts, and time controlled means actuated by the movement of the lever for opening and closing said circuit controlling means.

4. A mechanical time release for levers of 55 interlocking machines, comprising two side plates arranged side by side and separated by spacing studs, a contact block mounted on the edges of said plates and clamped in position by a hook bolt adapted to hook under one of said spacing studs and provided with clamping nuts for holding the block, circuit controlling means carried by said contact block and secured thereto by binding posts, and time controlled means actuated 60 mechanically by the movement of the lever for locking and unlocking said lever and for opening and closing the circuit controlling means in accordance with the locked and unlocked condition of the lever.

5. In a time release mechanism of the character described, the combination with the locking bolt, its latch and the spring actuated time controlled means for releasing the latch, of adjustable means for varying 75 the extent of winding movement of the time controlled means for the same movement of the locking bolt, and a pallet adapted to have weights attached thereto, whereby coarse and fine adjustments of the timing 80 operation of said mechanism may be obtained.

RICHARD C. LEAKE.
